BANK CHECK COVER

Sidney B. Klahn, Portland, Oreg.

Application March 23, 1942, Serial No. 435,771

1 Claim. (Cl. 281—17)

This invention relates generally to banking and particularly to a bank check cover.

The main object of this invention is to construct a bank check cover which would be easy to manufacture, neat in appearance, devoid of outside flaps, and avoiding the use of snap fasteners for holding the cover in a closed position.

The second object is to make possible the manufacture of bank check covers during emergency conditions while the common type of snap fasteners are not obtainable.

These and other objects are accomplished in the manner set forth in the following specification, as illustrated in the accompanying drawing, in which:

Fig. 1 is a plan of the bank check cover showing it opened to its full length.

Fig. 2 is a side elevation of Fig. 1.

Fig. 3 is a front elevation of the closed bank check cover.

Fig. 4 is a side elevation of the closed bank check cover.

Fig. 5 is a rear elevation of the closed bank check cover.

Fig. 6 is a rear end elevation of the closed bank check cover.

Fig. 7 is a front end elevation of the bank check cover.

Similar numerals refer to similar parts throughout the several views.

Before entering into an explanation of this invention, it must be understood that numerous forms of bank check covers have been constructed in the past. Nearly all of these devices employ snap fasteners for securing the cover in a closed position. Owing to the difficulty of obtaining metallic snap fasteners under the present conditions, the manufacture of these devices has been seriously hampered, and it is to overcome this difficulty as well as to improve the appearance and durability of the bank check covers that I have directed my invention.

Referring in detail to the drawing, there is shown a front 10, having a front lining 11 attached thereto along the edges 12 and 13. The edge 14 of the lining 11 extends a short distance back of the edge 15 of the front 10. The front 10 is integral with and attached to the back 16

while the back lining 17 extends from the edge 18 to the edge 13 of the front lining 11 and is preferably integral therewith.

The edge 18 is spaced a considerable distance from the flap hinge 19 from which the flap 20 tapers to the end 21. The sides 22 of the flap 20 have the rounded corners 23 to facilitate the ready insertion of the flap 20 into the pocket formed between the front 10 and the lining 11. The usual bank book 24 may be inserted in the back 16 and the back lining 17.

It can be seen by referring to Figs. 3 to 7 that the closed bank check cover is devoid of snaps or projections of any kind which might catch on the pocket or become creased or bent from use. In some cases it will be found desirable to round the corners 25 to still further insure against the cover being caught on the pocket or other objects, and to reduce the chance of mutilation.

It can be seen from the foregoing that the bank check cover herein described is not only easy to manufacture but inexpensive to manufacture under normal conditions and possible to manufacture under conditions when the usual clasps or snaps are not available, and in addition thereto, the resulting cover is thinner than the snap closed cover by a distance equal to the height of the snap post plus the thickness of the snap button.

In actual practice, the tab 26 of a check pad 27 is inserted back of the edge 14, that is, between the front 10 and the front lining 11 while the flap 20 is inserted between the tab 26 and the front 10.

I claim:

A snapless bank check cover consisting of a front and a back of substantially equal dimensions and hinged along on adjacent pair of edges, the front thereof having a pocket whose opening is spaced slightly from the end of the front, the back thereof having a tapering flap hinged to its outer end the taper and length of the flap permitting same to occupy said pocket when the front and back are folded together and to hold said front and back in closed relationship leaving the flap hinge concealed behind the edge of the front.

SIDNEY B. KLAHN.
